By # UNITED STATES PATENT OFFICE.

RICHARD H. YOUNIE, OF HAWARDEN, IOWA.

RAILWAY-TIE.

1,169,905.

Specification of Letters Patent.

Patented Feb. 1, 1916.

Application filed July 13, 1915. Serial No. 39,645.

To all whom it may concern:

Be it known that I, RICHARD H. YOUNIE, a citizen of the United States, residing at Hawarden, in the county of Sioux, State 5 of Iowa, have invented certain new and useful Improvements in Railway-Ties; and I do hereby declare the following to be a full, clear, and exact description of the invention, such as will enable others skilled 10 in the art to which it appertains to make and use the same.

This invention relates to improvements in railway ties, and particularly to metallic railway ties and rail fasteners carried 15 thereby.

One object of the invention is to provide a rail tie of such construction that it will be strong and durable to support the rails, and which will also aid in preventing 20 spreading of the rails.

Other objects and advantages will be apparent from the following description when taken in connection with the accompanying drawing.

25 In the drawing: Figure 1 is a side elevation of a tie made in accordance with my invention, the rails being shown in section, Fig. 2 is a top plan view of the same, Fig. 3 is a transverse section on the line 3—3 of 30 Fig. 2, and Fig. 4 is a longitudinal section on the line 4—4 of Fig. 2.

Referring particularly to the accompanying drawing, 10 represents an elongated hollow metallic member forming the body 35 of the tie. Formed transversely in the top of the tie, adjacent each end is a slot 11, the same extending across the tie from one side to the other. At each end of the slot 40 is an outwardly extending horizontal lip 12, the purpose of which will appear later. At each side of the slot there are formed a pair of openings 13 in which are received the tongues 14 of the clamp plates 15. Formed in the center of each of these plates 45 is a bolt opening 16, while in the top of the tie beneath this opening is formed a thread-

ed opening 17. Disposed in each end of the tie beneath the slot is a reinforcing box-like structure 18, and in this box and registering with the threaded openings 17 are 50 threaded openings 19.

A rail 20 is placed on the tie so that its base rests on the top of the box-like member within the slot. The clamp plates 15 are then engaged with the openings 13 in 55 such position that they rest on the base of the rail. Bolts are passed vertically through the openings of the plates and screwed into the openings of the tie and the box. When the bolts are screwed down, the plates 15 are 60 clamped firmly against the rail so as to hold the same down in the groove. The laterally directed lips 12 receive the rail base thereon and aid in supporting the same. It will thus be seen that the clamps 15 hold 65 the rail down in the slot so that the edges of the base of the rail are prevented from movement toward or away from the other rail by the side walls of the slot.

The fact that the bolts are threaded into 70 the top of the tie and the reinforcing member obviates the use of nuts.

What is claimed is:

A railway tie and rail fastening comprising a hollow metallic body having transverse 75 openings adjacent the ends thereof for the reception of rail bases, a reinforcing box-like structure disposed within the ends of the body beneath the rails, said body and reinforcements being formed with register- 80 ing openings and threaded openings, clamp plates having tongues disposed through the said slots, and openings registering with the threaded openings, and bolts engaged through the clamp plates and threaded into 85 the threaded openings.

In testimony whereof, I affix my signature, in the presence of two witnesses.

RICHARD H. YOUNIE.

Witnesses:

Mrs. R. H. YOUNIE,
JOHN RING.
